UNITED STATES PATENT OFFICE.

WILLIAM F. MARRESFORD, OF BROOKLYN, NEW YORK.

MACHINE FOR MAKING WALL-PAPER CUT-OUTS.

1,223,893.

Specification of Letters Patent.

Patented Apr. 24, 1917.

Application filed April 6, 1914. Serial No. 829,755.

To all whom it may concern:

Be it known that I, WILLIAM F. MARRESFORD, a citizen of the United States, residing at Brooklyn, in the county of Kings and 5 State of New York, have invented certain new and useful Improvements in Machines for Making Wall-Paper Cut-Outs, of which the following is a full, clear, and exact specification.

10 This invention relates to machines for making wall paper cutouts, and has particular reference to a novel combination of driving and adjusting means for a design cutting-out mechanism, whereby the cutters are 15 capable of making a varying length of cut so as to register with the pattern as printed.

When a web of wall paper intended for a cutout is printed, it tends to stretch unevenly, so that in some instances there is a 20 considerable variation in the length of different patterns on the printed web. When it is sought to cut such a pattern by a rotary cutter having a normal length of cut equal to one or a partial revolution, it is found 25 that the cut will not register with the pattern unless the pattern is of exactly the same length throughout. By this machine, it is possible to vary the length of cut of a rotary cutter without tearing the paper, while the 30 machine is running, and it is also possible to properly start the cutter in registry with the design to be cut. A further result attained by this invention is in the use of a rotary platen in combination with a rotary 35 cutter, and driven in such manner that the paper will neither be torn nor buckled notwithstanding a difference between the circumferential length of the platen and the circumferential pitch length of its driving 40 gear. By this feature of the invention, the platen can be shaved down when worn without requiring change of the driving gears, and also it becomes immaterial whether the 45 peripheral speed of the platen is the same as that of the pitch circle of its driving gear or not. A greater range of adjustment is also permitted between the cutter and the platen for controlling the depth and character of cut made in the paper. Convenient 50 means for lateral adjustment of the cut with relation to the pattern is also provided.

The invention with reference to one form thereof is shown in the accompanying drawing, wherein—

Figure 1 is a side elevation of the machine 55 embodying this invention;

Fig. 2 is an end view partly in section; and

Fig. 3 is a plan view of the supply end 60 of the machine.

The machine has a frame 1, and is driven in any suitable manner from a shaft 2 having a gear 3 which meshes with an idler 4 adjustable in the slotted segment 5, which drives a gear 6 loose on shaft 7. The shaft 65 7 carries a cutter roller 8 having a cutter 9. The cutter 9 may be of any form known to the art, and as herein shown consists of a large number of small cutting knives or perforators arranged on the periphery of roller 70 8 to cut the required design. The design to be cut may require a complete revolution of the roller 8, or it may be repeated, as desired. Axial adjustment of cutter roll 8 is provided for as follows: cutter roll shaft 7 75 is journaled in adjustable bearings 45 which have depending ears 46. Through the latter arm the frame arm 32 passes a screw 47 having a hand wheel 48. By turning the hand wheel, the bearing 45 and with it the 80 cutter roller 8 is adjusted parallel to the platen roll 14. The drive between gear 6 and shaft 7 is so arranged as to permit a relative shifting of the gear 6 and cutters 9, so that the cutters 9 are adjustable back- 85 ward or forward through an angle of rotation sufficient to enable the length of cut to be varied during a predetermined rotation. For example, the predetermined rotation may be taken as one complete revolution. 90 This result is effected by a worm gear 10 which is keyed to shaft 7, and the gear 6 carries a worm 11 which meshes with worm gear 10. Thus, the drive is from gear 6 through worm 11 to worm gear 10, and 95 thence to shaft 7 and cutters 9. The worm gear 11 is provided with a hand wheel 12 so that it can be revolved either while the machine is at rest or while the machine is running, and thereby shift the cutters 9. 100 By revolving the worm 11 and thereby the cutters 9 while the machine is at rest, the

cutters can be exactly registered with the printed design, while by turning the worm 11 while the machine is running, a differential movement between the driving gear 6 and the cutters 9 can be effected either forwardly or backwardly, (depending upon the way the worm 11 is rotated), and thereby the length of cut will vary relatively to the length of the printed pattern. In other words, the cutters can be either angularly advanced or angularly retarded while the machine is running, and thus the length of cut made to register with the length of the printed pattern. This will be done by the operator who, after slight experience, will become so expert as to make the cut exactly coincide with the printed pattern, notwithstanding the variations in the length of the printed pattern due to the uneven stretching, warping or contraction of the paper. This shifting of the cutters relatively to the paper while the paper cutters are moving will be so gradual at any point as not to tear the paper, and yet the sum of this gradual shifting, while hardly perceptible at any one point, will bring the cut and the printed pattern back into registry. It is thus evident that while the cutter has a normal length of cut approximating its circumferential length, the actual cut it makes can be varied to be either more or less than its normal length. 14 represents a platen cylinder, which is driven by shaft 15. The shaft 15 is carried by opposite links 16 pivoted on the frame 1 at 17 and supported by links 18 pivoted at 19 to a lever 20. The lever 20 is pivoted on the frame 1 at 21 and is supported by an adjustable screw 22. By adjusting the screw 22 the position of the platen relatively to the cutters 9 will be controlled, and thereby the depth of cut. The lever 20 is provided with a chain 23 and hook 24, which latter can be engaged with a pin 25 when it is desired to hold the platen elevated above the cutters 9 for the insertion of the paper. In order to provide for the variation of diameter between the platen 14 and the pitch circle of its driving gear 26, a frictional disk drive is provided. This consists of a disk 28 attached to gear 26 and a second disk 29 attached to shaft 15, between which is interposed the friction disk 27. The gear 26 is loose on shaft 15 and is pressed against the friction disk 27 by spring 30 abutting against an end collar 31. Thus, the engagement of the cutters 9 with the surface of the platen 14 will act similarly to a brake and allow the friction drive to slip, so that the peripheral speed of the platen 14 will always be equal to that of the cutters 9, irrespective of the driving gears. This obviates considerable changing of gears when the pattern is changed. For example, the pattern cutters 9 will have to be changed with each different pattern, but

by this mechanism it will be unnecessary to correspondingly change the driving gear 26, since the friction drive will take care of all variations without imposing any objectionable strain on the paper, as would otherwise happen if the drive were faster or slower than the peripheral speed of the platen and cutters. Gear 6 may be changed where the cutting roll diameter is changed.

The gears 4 and 6, and the cutter roller 8 with its shaft 7, are preferably mounted in a swinging frame 32, which swings about shaft 2 so that the cutter roller can be dropped clear of the platen roller when desired. The frame 32 is adjustably supported by a pin 33 which is inserted through holes 34 in frame 32 into the frame 1. By this arrangement, the adjustable frame 32 may be changed in position to accommodate cutter rollers of different diameters, which in the art would normally correspond with various standard diameters of printing rolls used for printing the design which it is desired to cut. 36 represents the web which is laterally centered in the machine by a transversely adjustable flanged roller 37, and thence the web 36 runs under and over tension rollers 38 and out to the winding up machine. 39 is a set screw for transversely adjusting the flanged roller 37.

From the foregoing description, it will be seen that the present invention provides a machine containing adjustments for meeting the practical conditions and variations incident to the manufacture of decorative cutouts. The adjustments not only permit the machine to be adjusted while at rest to properly start the cutter in registry with the design, but enable this registry to be maintained while the machine is running by varying the length of cut produced by the roller cutter from its normal length of cut.

Various modifications and changes may be made without departing from the scope of the appended claims.

Having thus described my invention, I declare that what I claim as new and desire to secure by Letters Patent, is:—

1. The combination with rotary design cutting means, and a co-operating rotary platen, of meshing driving gears therefor, and frictional driving means between the platen and its driving gear rendering the peripheral speed of the platen and the cutter independent of the speed of said driving gears.

2. The combination of a driven platen, a pattern cutting roll geared to be driven therewith, means for angularly adjusting the cutting roll relatively to the platen, and means permitting the platen to slip relatively to its driving means.

3. The combination with a positively driven bodily swinging platen, of a swinging pattern cutting roll geared to be driven

with said platen, said cutting roll and platen bodily swinging toward and from each other, means for angularly adjusting the cutting roll relatively to the platen, and means 5 permitting the platen to slip relatively to its driving means.

In testimony whereof I affix my signature, in presence of two witnesses.

WILLIAM F. MARRESFORD.
